CLAIM

The ornamental design for a LED desk lamp, as shown and
described.

DESCRIPTION

FIG. 1 is a perspective view of a LED desk lamp, showing
my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of FIG. 1; and,

FIG. 9 is a perspective view of the LED desk lamp in an
alternate state of use.

The short-short-long dashed broken lines immediately adjacent
to the claimed areas in FIG. 5 represent the boundaries
of the design and form no part of the claimed design.

The other broken lines in the figures are for the purposes of
illustrating portions of the LED desk lamp, which form no
part of the claimed design.
